REFRIGERATION

Henry E. Stevens and James W. Windham, Jacksonville, Fla., and George C. Albee and Esty Foster, South Orange, N. J.; said Stevens and said Windham assignors of all their rights to said Albee

Application January 19, 1933, Serial No. 652,524

7 Claims. (Cl. 62—48)

The present invention relates in general to refrigeration and has particular reference to mechanical refrigerators, cooling cabinets, ice boxes and the like commonly used for preserving food stuffs in households, restaurants and under other like conditions.

So called mechanical refrigerators of the type indicated are usually equipped with grille like shelves for supporting the food stuffs in one large exposed compartment. Under these conditions when the door of the refrigerator is opened, the entire refrigerating area of the refrigerator is exposed to room temperature. As a result the cold air, which is produced at a certain amount of expense, is dissipated and the space is filled with warm air from the room. This makes it necessary for the mechanism of the refrigerator to function in cooling the admitted warm air. As a result of these operating conditions not only is the expense in maintaining a refrigerator a considerable item to contend with, at least compared to what it would be, under more favorable conditions, but the varying temperatures brought about by opening the door results in deterioration of the food.

The primary object of our invention is to overcome the inefficiency of the present type of refrigerators by equipping the same with individual storing compartments which are selectively accessible for the insertion or removal of food stuffs without, not dissipating the cold air in all of the other compartments, but preserving almost all of the cold air in the particular compartment into which access is had.

Other objects of the invention will appear hereinafter, the novel features and combinations being set forth in the subjoined claims.

Obviously those skilled in the art may make various changes in the construction and arrangement of parts without departing from the spirit and scope of the invention as defined by the claims hereto appended, and we therefore do not wish to be restricted to the precise construction contained herein.

The invention is exemplified in the arrangement of parts shown in the accompanying drawings and described in the following specification.

In said drawings:

Fig. 1 is a view of the front elevation of a refrigerator constructed in accordance with our invention;

Fig. 2 is a view in vertical section on the line 2—2 of Fig. 1;

Fig. 3 is a cross section on the line 3—3 of Fig. 1;

Fig. 4 is a view in cross section on the line 4—4 of Fig. 1;

Fig. 5 is a detail view in perspective of the operating arm for the compartment ventilating shutters;

Fig. 6 is a detail view in section of a drop cover for one of the compartments;

Fig. 7 is a detail view of the shutter operating mechanism, and

Fig. 8 is a similar view with the mechanism in a different operating position.

Referring now to the drawings in detail 5 represents a refrigerating box which may be made in any manner suitable for the purpose and, as is customary, having a door 6 which is hinged as at 7 adjacent its top and bottom at the front of the box 5.

In the showing made the invention has been illustrated as applied to that type of box having a single door. In practice this is not of any particular significance as the advantages of the invention may be realized in combination with a box having two or more doors for obtaining access to the contents of the box. As a matter of fact the type of box has little, if anything, to do with the application of the invention. This same reasoning holds true in connection with the type of refrigeration employed. The refrigeration may be of electro-mechanical type or of the gas type. As a matter of fact the invention is also applicable to ice boxes.

According to the invention instead of dividing the storage space of the box into a tier or tiers of grille like shelves, as is customary, we propose to divide the space into a series of individual drawer like compartments. As illustrated only two of these compartments are shown in addition to the freezing compartment and the other compartment along side the same. As a matter of fact any number of compartments may be employed depending upon the way it is desired, to divide up the space. The present showing, however, is sufficient for the purpose of illustrating the advantages and the construction of the invention.

Each of these compartments preferably comprises a drawer structure having a front wall 8 a back wall 9 side walls 10 and a bottom 11. The top being open. Each drawer is intended to slide on ledges, rods or the like which are fixed within the box in proper spaced relation. The bottom 11 of each drawer is made with spaced openings 12 which are oblong in shape as best shown in

Figs. 3 and 4. The upper edges of these openings are made with rims 13 to serve as knife edges on which the shutters 14 slide. The purpose of providing these knife edges is to offer a pointed, or in other words, a relatively sharp sliding contact for the shutters 14 so as to avoid the possibility of collecting moisture and retarding or otherwise defeating the free sliding movement of the shutters. These contact rims 13 also support the shutters 14 in spaced relation relative to the bottom of the drawer between the openings 12. The food stuff occupying each drawer is supported by a grille 15 so as to hold it away from the operating action of the shutters and also to allow for circulation, not only around the food, but under the same as well.

The ventilating openings 12 of each drawer are arranged in any manner suitable for the purpose, but for all practical purposes it is proposed to 20 arrange a series on opposite sides of the center line of the drawer and preferably, from front to rear at spaced intervals.

The shutters 14 are preferably made in the form of a sheet metal blank cut to approximately 25 correspond to the dimension of the bottom of the drawer. It will be smaller however, because the shutters slide from front to rear and this sliding movement must be accounted for. When the shutters are at the limit of their rearward 30 movement the openings 16 are out of register with the openings 12 consequently the spaces 17 between the openings 16 overlie the openings 12 and close the same.

The shutters for each of the drawers are 35 collectively operated automatically by the opening and closing of the refrigerator doors 6 so that when the door 6 is open the shutters will be collectively operated to close the openings 12 and thus shut off circulation in all the drawers.

Otherwise stated the object of the invention is 40 to prevent the escape of the cold air from all of the compartments. Now then, if access is desired into any compartment the door 6 is of course opened and the act of opening the door 45 6 will close the openings into all of the compartments. With the openings in all of the compartments thus closed any drawer or drawers may be pulled out to obtain access thereto. The shutters remaining closed when the drawer is 50 opened.

The operating mechanism for opening and closing the shutters in each drawer comprises in its simplest form a headed pin 18 which is fixed to the web 19 of each shutter and thus supported 55 to work in a slot 20 in the bottom of the drawer. The lower end of the pin is equipped with a diamond or triangular shaped block 21. It now follows that by imparting a push to the pin 18 the shutter will slide rearwardly into its terminal 60 position with the pin at the rear end of the slot 20 and the spaces 17 between the openings 18 overlying the openings 12 thus closing the same. By imparting a forward pull to the pin 18 the shutter will be moved forward to register the 65 openings 16 with the openings 12 thus establishing a communication between the interior of the drawer.

It is desired to automatically close the shutters 70 collectively when the door 6 is opened and to automatically open the shutters collectively when the door is closed. To accomplish this objective an operating arm 22 is supported under each drawer by a pivoted connection as at 23 supported by the ledge, or an extension thereof on which the drawer slides. The extremity of the arm is

formed with an eye 24 through which an operating rod 25 is passed. The rod is equipped with fixedly spaced collars 26 between which the eye 24 works so as to impart the necessary pull or push to the end of the arm 22. The movement of each arm is developed by the operating rods 25 which extend forwardly through the front wall 27 of the box. This wall 27 serves as a frame for the drawers and co-operates therewith in enclosing the refrigerating space within the box. The wall 27 is made with an opening through which each of the operating rods 25 protrude.

Each rod is under the influence of a spring 28 which is coiled around the same between the face of the wall 27 and a collar 29 fixed on the rod. Furthermore, each rod has a diamond shaped operating head 30 which co-operates with the clevis like jaws 31 carried by the door 6.

When the door 6 is closed the clevis like jaws 31 bear against the collars 29 and thrust the rods 25 against the influence of the springs 28. This thrust imparted to the rods 25 will cause the operating arms 22 to swing about their pivots 23. The end of each of the operating rods 22 is made with a relatively long curved finger 32 and a heel 33. When the rods 25 are thrust inwardly, by the act of closing the door as previously stated, the swinging movement of the arms will cause the fingers 32 to engage the diamond shaped blocks 21 and pull the pins 18 forward which in turn 105 slide the shutters to open the ventilating openings as above described.

When the door is opened the springs 28 will exert their influence and pull the rods 25 outwardly which will cause the operating arms 22 to 110 swing into a position where the heels 33 thereon will engage the diamond shaped blocks 21 and slide the shutters rearwardly to close the ventilating openings.

From the above it will thus be seen that all of 115 the shutters are collectively closed when the door is opened and collectively opened when the door is shut, consequently when the door is opened to remove and replace anything in the compartments, all drawers will be unaffected by any 120 change in temperature, all being sealed on all sides and the bottoms of the drawers and the greater weight of the cold air keeping it all practically within their confines.

In the event that a sliding movement of the 125 rods 25 is interfered with in any particular it will be possible to help the springs 28 by means of the clevis like jaws 31. In this respect the rods 25 are mounted for limited rotating movement by means of the offset slot 34 on each rod. A detent 130 35 rides in these slots 34 to limit this rotary movement. Each of the detents are fixed to the back of the wall 27 adjacent the rods.

With the rods mounted for limited rotary movement as described the act of closing the 135 door will cause the inside edge of the clevis like jaws 31 to ride the side of the diamond shaped heads 30 thus rotating the rods and positioning the inturned ends of the jaws behind the head. When the door is opened the inturned ends of the 140 jaws ride the sides of the head and there will be just enough friction to impart a slight pull to the rod before the head is released from the jaws and this slight pull will be sufficient to overcome any resistance to the sliding movement of 145 the rods thus making sure that the springs will properly function.

The shape of the finger 32 and heel 33 on each of the operating rods 22 is of importance because the outward sliding movement of the drawers is 150

greater than the range of the swinging movement of the operating arms consequently it becomes necessary to disconnect the operating arms from the drawers to permit the drawers to be pulled out all the way or even three quarters of the way. This is accomplished by the particular design of the finger 32 and heel 33. When the operating arms are in a position to close the shutters the heel 33 will have come to rest in a position as shown in Fig. 4 where it is entirely clear of the co-operating block 21. This clearance is further accounted for by the shape of the blocks. Any one of the drawers may then be pulled out without interfering with the operating area. When the drawer is pushed back into place the ventilating openings will remain closed until the door 6 is closed whereupon the finger 32 will operate to pull the shutters forward and open the ventilators.

While the foregoing description has been devoted to the two lower drawers it should be explained that the unit 36 in the top of the box may be made with a sliding drawer and also having the ventilating openings with the same shutter arrangement. The same shutter arrangement is also provided for the freezing unit 37. In this freezing unit 37 however, a sliding drawer is dispensed with and a drop door 38 is used. This door is hinged as at 39 at the top and is lifted up to obtain access to the compartment 37. The door 38 is hung so that it will close under its own weight. The opening into the compartment 37 is made with a knife edge 40 around the same for the same reasons as explained with reference to the sliding movement of the shutter 14 on the bottom of the drawers.

Since there is no sliding drawer in the freezing unit 37 the operating rod 41 therefore need not be equipped with the fingers and it is only necessary to pivot the same as at 42 to the frame with the opposite end of the arm pinned to the shutter as at 43. In the case of the other side of top section 36 which does have a pull out drawer the fingers are utilized. In this case the operating arm 22' is pivoted as at 23' with its end connected to the central operating rod 25' along side of the connection to the operating arm 41. The operating arm 25' is arranged in the center instead of to one side as in the lower compartments. It operates in the same manner as described with reference to the lower compartments except that it serves both sets of shutters 14'. The clevis like jaw 31' for this rod is positioned in the center of the door 6 as shown in Fig. 1.

As indicated by the arrows in Fig. 1 a continuous unobstructed circulation is provided for behind the wall or frame 27 so that the cold air will continue to circulate from top to bottom in and out the drawers or compartments. When the door 6 is open however, this circulation is interrupted because all of the shutters are closed but just as soon as the door 6 is closed the shutters are all opened simultaneously and the circulation can then continue. In order to encourage this circulation from top to bottom so that it will go down one side and come up the other side it is proposed to hang curtains 44 part way down in each drawer parallel with the center line of the drawers. The curtains may be suspended from rods 45 which extend from front to rear of the drawers and carried by the front wall or frame 27 and the rear inside wall of the box. This arrangement of curtains will discourage cross circulation and encourage up and down circula-

tion through the freezing unit which of course is highly desirable.

Each drawer should be equipped with a limit stop 46 which will determine the extent to which it may be pulled out in obtaining access to the contents of the same.

From the above it will be seen that the present invention has many possibilities in maintaining even low temperatures in refrigerators even though the door of the box is frequently opened. Such an arrangement will not only be a considerable saving in operating cost but it is a more complete scientific treatment for food stuffs and when it is considered that these accomplishments are arranged with a small number of operating parts with nothing to get out of order it can be appreciated what an improvement it is over the customary manner of constructing such an equipment.

For convenience the front of each drawer will be equipped with a glass panel so that the contents of the drawers may be examined without opening the drawers and looking for any particular article that is desired.

Furthermore, all of the food in the drawers is conveniently accessible without reaching back of any shelf as in the conventional refrigerator.

Having thus described and shown an embodiment of our invention, what we claim and desire to secure by Letters Patent of the United States, 105 is:

1. A refrigerator having an interior storage space, a door for obtaining access to said space, a plurality of drawers in said space, air circulating openings in one of the walls of each drawer, 110 and closures for said openings operable by the opening and closing of said door.

2. A refrigerator having an interior storage space, a freezing unit for cooling said space, a plurality of drawers slidably mounted in said 115 space, each of said drawers having air circulating openings which provide for circulation between the drawers and the freezing unit, shutters for said openings and operating mechanism for opening and closing said shutters, comprising operating arms for the shutters and spring influenced operating rods connected to said arms and actuated by the door through which access is had into the refrigerator; to thereby cause the operating arms to close the shutters when said door is 125 opened and to open the shutters when said door is closed.

3. In a refrigerator a frame structure within said refrigerator, drawers mounted to slide in said frame structure, the front of said drawers co-operating with the front of the frame structure to provide an enclosed space within the refrigerator, a freezing unit for the refrigerator, each of said drawers and the freezing unit having a plurality of circulating openings to establish circulation between the drawers and the freezing unit, shutters for said openings and means actuated by the opening and closing of the refrigerator door for opening and closing said shutters.

4. In a refrigerator, a frame structure within 140 said refrigerator, drawers mounted to slide in said frame structure, the front of said drawers co-operating with the front of the frame structure to provide an enclosed space within the refrigerator, a freezing unit for the refrigerator, each of 145 said drawers and the freezing unit having a plurality of circulating openings to establish circulation between the drawers and the freezing unit, shutters for said openings and means actuated by the opening and closing of the refrigerator 150

door for opening and closing said shutters, comprising operating arms pivoted under each of the drawers, pins on the shutters extending through slots in the bottom of the drawers, operating heads on said pins, and means on the operating arms to engage said heads for sliding the shutters in opposite directions, actuating rods for said arms supported in the frame structure for sliding movement, springs on said rods to move the same outwardly when the door of the refrigerator is opened; to thereby close the shutters and means on the refrigerator door to impart a thrust to said rods against the resistance of said springs for opening the shutters when the refrigerator door is closed.

5. The combination as set forth in claim 4 and in which the means for engaging the heads of the pins clears the heads when the shutters are

closed; whereby the drawers are released for unlimited outward sliding movement.

6. The combination as set forth in claim 4 and in which the drawers are equipped with baffle like curtains suspended above the drawers from front to rear and along the center line of the drawers to direct an up and down circulation of air between the freezing unit and the drawers.

7. The combination as set forth in claim 4 and in which the shutters are mounted for sliding movement over the circulating openings and are supported for such sliding movement by upstanding knife edges provided at the edge of the circulating openings.
